HYDROCARBON OIL CONVERSION

Joseph G. Alther, Chicago, Ill., assignor to
Universal Oil Products Company, Chicago, Ill.,
a corporation of South Dakota

Application December 11, 1930, Serial No. 501,506

7 Claims. (Cl. 196—48)

This invention relates to the treatment of hydrocarbon oils and refers more particularly to the conversion of hydrocarbon oils into lower boiling products of a more valuable character, such as the production of motor fuels of high anti-knock value.

One of the most difficult problems facing the refiner of certain types of oils such as Pennsylvania and Muskegon crude oil, is the low anti-knock value of the gasoline which occurs naturally in the crude oils from these respective districts.

From an economic view point, my invention provides a process which permits the refiner to convert intermediate boiling fractions above the boiling range of gasoline into high yields of anti-knock motor fuel, which in addition to the advantages per se permits the refiner to utilize the product of my invention as a blending agent to increase the anti-knock value of the straight run motor fuel produced from the same or similar stock, thus facilitating its sale and making its use more desirable.

In one of its specific embodiments the invention provides a process which comprises subjecting hydrocarbon oils to heat treatment at conversion conditions, introducing the heated oil into an enlarged reaction zone, removing the total products comprising the non-vaporized oil together with vapors and gases and introducing the same into a vaporizing zone, separately withdrawing the non-vaporized oil from the vapors and gases, returning the reflux condensate from the fractionating zone to the heating zone for further conversion, subjecting the vapors to fractionation, and subsequently cooling, condensing and collecting them.

The accompanying diagrammatic drawing shows one form of apparatus suitable for carrying out my invention.

Referring in detail to the drawing, raw oil charging stock may be introduced through line 1 controlled by valve 2 and may be pumped by means of pump 3 through line 4 controlled by valve 5 into the fractionator 6, where it may preferably be brought into indirect heat exchange with the vapors arising therein by means of heat exchanger 7. The oil continues in its course through line 8 controlled by valve 9, through line 10 controlled by valve 11 and

through line 12 into heating element 13 disposed in a suitable furnace setting 14. If desired, the oil may be pumped directly into the heating element 13 through lines 10 and 12 controlled by valves 10' and 11. The purpose of indirect heat exchange in the fractionator or of directly charging the oil into the heating element is to prevent vaporization of some of the lower boiling components of the charging oil before subjecting them to conversion conditions, as these components would be collected with the low boiling product of the process and reduce considerably the anti-knock properties of the product.

The oil at conversion conditions may be discharged through line 15 controlled by valve 16 into the reaction chamber 17. The unvaporized residue together with vapors and gases may be discharged through line 18 controlled by valve 19 and passed into the vaporizing chamber 21. A small portion of the vapors with accompanying gases may be withdrawn through line 22 controlled by valve 23 and introduced directly into the fractionator 6 to assist in reboiling the reflux condensate therein and to separate any gases which may possibly become segregated from the vapors in chamber 17. The non-vaporized residue may be withdrawn from chamber 21 through line 24 controlled by valve 25. The vapors leaving the chamber 21 may pass through line 26 controlled by valve 27 and into the fractionator 6 wherein the vapors are fractionated. The reflux condensate from the fractionator 6 passes through line 28 controlled by valve 29 and is pumped by means of pump 30 through line 31 controlled by valve 32 and through line 12 into the heating element 13, where it may be subjected to cracking conditions for further conversion into lower boiling products.

The vapors leaving the fractionator 6 pass through line 33 controlled by valve 34 and through cooler and condenser 35 controlled by valve 36, the condensed vapors being collected in receiver 37. Gases may be withdrawn from receiver 37 through line 38 controlled by valve 39, which may also function as a pressure control valve upon the entire system or various parts thereof. The liquid accumulating in receiver 37 may be withdrawn through line 45 controlled by valve 46. A portion of the condensate may be returned through line 40 controlled by

valve 41 and pumped by means of pump 42 through line 43 controlled by valve 44 into the fractionator 6, where it serves to assist in cooling the vapors arising therein and to control the 5 fractionation thereof.

In some cases in order to overcome operating difficulties such as possible coking of the line 18, I have found it desirable to introduce suitable cooling oils from an external source, the arrangement for which is not shown but will be obvious 10 to those skilled in the art.

In the operation of the process it is desirable 15 to maintain substantially no liquid level in the reaction chamber 17, the hydrocarbon material undergoing reaction in the chamber being substantially in the vapor phase. The arrangement is such as to cause the hydrocarbon vapors to traverse substantially the entire length of the reaction zone, the main purpose of which is to obtain 20 the longest possible reaction time upon all of the hydrocarbon vapors in the reaction zone and to prevent short-circuiting of a portion of the hydrocarbon vapors. This permits maximum conversion and homogeneous treatment of the 25 hydrocarbons undergoing conversion. The temperature and pressure conditions employed may vary over a wide range and uniform or equalized pressures may be used throughout the system, or differential pressures may be employed on the 30 various elements thereof, varying from sub-atmospheric to high super-atmospheric pressures. Preferably relatively high super-atmospheric pressures may be employed on the conversion elements and relatively low pressures employed on vaporization, fractionating, condensing and receiving 35 elements.

While my process is suitable for the treatment 40 of hydrocarbon oils of both low and relatively high boiling ranges, comprising residual fuel oils, topped crude oils, gas oils, kerosene distillate, naphthas, including the reforming of gasoline, it has proven highly suitable for the treatment of 45 relatively low boiling or high gravity charging stocks; for example, Pennsylvania distillates varying in gravity from 36 to 46° A. P. I.

The following results which are illustrative only are given as examples of actual results

obtained by the operation of the process of my invention:

It is obvious from the results obtained, both in regard to yields and high anti-knock properties of

the product, especially when one considers the source of this product, that I have disclosed a highly useful process of broad scope and it is intended that the examples given are to be illustrative only and are not restrictive of the broad principles of the invention.

“Kerosene distillate” as used herein is intended to define a hydrocarbon distillate product which has a boiling range substantially within the range of an initial boiling point of 300° F., and an end point of 650° F.

While I have illustrated the invention specifically used in kerosene distillate of Pennsylvania origin, it is to be understood that the invention is not to be limited to the use only of kerosene distillate from Pennsylvania. Kerosene distillates of any origin are contemplated for treatment according to the present invention under equivalent conditions to those specified in the illustrative runs for obtaining equivalent results.

I claim as my invention:

1. A process for converting kerosene distillates into liquid products of lower boiling point range, which comprises forcing a stream of such distillate through a heating zone and raising it to a conversion temperature, discharging said heated products from the heating zone into the upper portion of an enlarged vertical reaction zone, withdrawing substantially all of the products of reaction from the lower portion of said reaction zone and discharging same into an enlarged separating zone wherein vapors separate from non-vaporous residue, subjecting the vapors separated in said separating zone to fractionation in a fractionating zone, removing from an upper portion of said reaction zone a relatively small proportion of the gaseous and vaporous products of reaction and discharging same directly into the lower portion of said fractionating zone, subjecting the vapors in said fractionating zone to fractionation to condense the heavier fractions thereof as reflux condensate, removing said reflux condensate and admixing same with the stream of kerosene distillate being forced through the heating zone, removing the vapors remaining uncondensed after passage through the fractionating zone and

condensing and collecting the distillate resulting therefrom as the product of the process.

2. A process for converting kerosene distillates into liquid products of lower boiling point range, which comprises forcing a stream of such distillate through a heating zone and raising it to a conversion temperature, discharging said heated products from the heating zone into the upper portion of an enlarged vertical reaction zone, withdrawing substantially all of the products of reaction from the lower portion of said reaction zone and discharging same into an enlarged separating zone wherein vapors separate from non-vaporous residue, removing the residue from said separating zone and isolating same from the system, subjecting the vapors separated in said separating zone to fractionation in a fractionating zone, removing from an upper portion of said reaction zone a relatively small proportion of the gaseous and vaporous products of reaction and discharging same directly into the lower portion of said fractionating zone, subjecting the vapors in said fractionating zone to fractionation to condense the heavier fractions thereof as reflux condensate, removing said reflux condensate and admixing same with the stream of kerosene distillate being forced through the heating zone, removing the vapors remaining uncondensed after passage through the fractionating zone and condensing and collecting the distillate resulting therefrom as the product of the process.

3. A process for converting kerosene distillates into liquid products of lower boiling point range, which comprises forcing a stream of said kerosene distillate through an elongated passageway exposed to heat and raising said distillate to a cracking temperature, discharging said heated stream into the upper portion of an enlarged vertical reaction zone, maintaining superatmospheric pressure in said elongated passageway and in said reaction zone, removing substantially all of the vaporous and liquid products of reaction from the lower portion of said zone and discharging same into a zone of reduced pressure wherein vapors separate from non-vaporous residue, directing said separated vapors to a fractionating zone, removing from an upper portion of said reaction zone a relatively small proportion of the gaseous products of reaction and discharging same directly into the lower portion of said fractionating zone, subjecting the vapors in the fractionating zone to fractionation to condense the heavier fractions thereof as reflux condensate, removing said reflux condensate and admixing same with the stream of kerosene distillate being forced through the elongated passageway in the heating zone.

4. A hydrocarbon oil cracking process which comprises passing the oil in a restricted stream through a heating zone and heating the same therein to cracking temperature under pressure, discharging the heated oil directly from the heating zone into the upper portion of an enlarged vertical reaction zone maintained under cracking conditions of temperature and pressure, passing the unvaporized oil and the major portion of the vapors downwardly through said reaction zone and removing the same as a mixture from the lower portion thereof, the unvaporized oil being withdrawn from the reaction zone at such a rate that no appreciable liquid accumulation occurs therein, separately removing the remaining minor portion of the vapors from the upper portion of the reaction zone, discharging the mixture with-

drawn from the lower portion of the reaction zone into a separating zone maintained under lower pressure than the reaction zone and separating the same therein into vapors and residue, introducing the thus separated vapors into a fractionating zone and dephlegmating the same therein to condense insufficiently cracked fractions thereof as reflux condensate, introducing said remaining portion of the vapors into the fractionating zone and contacting the same with reflux condensate formed therein, and finally condensing the vapors uncondensed in the fractionating zone. 80

5. A hydrocarbon oil cracking process which comprises passing the oil in a restricted stream through a heating zone and heating the same therein to cracking temperature under pressure, discharging the heated oil directly from the heating zone into the upper portion of an enlarged vertical reaction zone maintained under cracking conditions of temperature and pressure, passing the unvaporized oil and a major portion of the vapors downwardly through said reaction zone and removing the same as a mixture from the lower portion thereof, the unvaporized oil being withdrawn from the reaction zone at such a rate that no appreciable liquid accumulation occurs therein, separately removing the remaining minor portion of the vapors from the upper portion of the reaction zone, discharging the mixture withdrawn from the lower portion of the reaction zone into a separating zone maintained under lower pressure than the reaction zone and separating the same therein into vapors and residue, introducing the thus separated vapors into a fractionating zone and dephlegmating the same therein to condense insufficiently cracked fractions thereof as reflux condensate, introducing said remaining portion of the vapors into the fractionating zone and contacting the same with reflux condensate formed therein, returning reflux condensate from the fractionating zone to the heating zone, and finally condensing the vapors uncondensed in the fractionating zone. 90

6. A process for converting fuel oil into liquid products of lower boiling point range, which comprises forcing a stream of such oil through a heating zone and raising it to a conversion temperature, discharging said heated products from the heating zone into the upper portion of an enlarged vertical reaction zone, withdrawing substantially all of the products of reaction from the lower portion of said reaction zone and discharging same into an enlarged separating zone wherein vapors separate from non-vaporous residue, subjecting the vapors separated in said separating zone to fractionation in a fractionating zone, removing from an upper portion of said reaction zone a relatively small proportion of the gaseous and vaporous products of reaction and discharging same directly into the lower portion of said fractionating zone, subjecting the vapors in said fractionating zone to fractionation to condense the heavier fractions thereof as reflux condensate, removing said reflux condensate and admixing same with the stream of fuel oil being forced through the heating zone, removing the vapors remaining uncondensed after passage through the fractionating zone and condensing and collecting the distillate resulting therefrom as the product of the process. 110

7. A process for converting gas oil into liquid products of lower boiling point range, which comprises forcing a stream of such distillate through a heating zone and raising it to a conversion tem- 120

perature, discharging said heated products from the heating zone into the upper portion of an enlarged vertical reaction zone, withdrawing substantially all of the products of reaction from the lower portion of said reaction zone and discharging same into an enlarged separating zone wherein vapors separate from non-vaporous residue, subjecting the vapors separated in said separating zone to fractionation in a fractionating zone, removing from an upper portion of said reaction zone a relatively small proportion of the gaseous and vaporous products of reaction and discharging same directly into the lower portion of said fractionating zone, subjecting the vapors in said fractionating zone to fractionation to condense the heavier fractions thereof as reflux condensate, removing said reflux condensate and admixing same with the stream of gas oil being forced through the heating zone, removing the vapors remaining uncondensed after passage through the fractionating zone and condensing and collecting the distillate resulting therefrom as the product of the process.
